TRIM ASSEMBLY

Maurice Stubnitz, Adrian, Mich., assignor to Stubnitz-Greene Spring Corporation, Adrian, Mich., a corporation of Michigan

Application December 6, 1935, Serial No. 53,142

6 Claims. (Cl. 155—180)

This invention relates to a trim assembly and more particularly to a trim assembly for a spring cushion seat.

It is an object of this invention to produce a trim assembly in which the trim material is effectively secured to the supporting frame with greater facility and lesser cost than in trim assemblies heretofore known.

In the drawing:

10 Fig. 1 is a fragmentary vertical section through a seat.

Fig. 2 is a fragmentary horizontal section through a seat showing the spacing of the slats and trim retainers.

15 Fig. 3 is a detail showing of a retainer being forced into the frame pocket.

Fig. 4 is a detail of a modified form of a retainer.

Fig. 5 is a section along the line 5—5 of Fig. 2.

Referring more particularly to the drawing 20 there is shown a seat assembly comprising a frame 1 which in section is substantially in the form of a reversed J or inverted question mark. This frame 1, which is preferably a continuous length of rolled metal, extends completely around 25 the seat bottom and is reinforced by slats 2 which extend in a fore and aft direction between the front and rear transverse portions of the seat frame. The slats 2 are provided with a return bent flange 3 at each end which is fitted over 30 the upper edge of the frame member. Thereafter corresponding depressions 4 and 5 are pressed into the return bent portion 3 and frame portion 1 to lock the slats to the frame. The frame is offset as at 20 so that the outside lip 35 of the return bent portion 3 is flush with the outer surface of the frame member 1 and thus secured against lateral displacement.

The slats support the usual coil springs 6 which in turn support the padding material 7. The cushion material 7 is covered with any suitable 40 trim material 8 such as fabric or leather.

The invention is particularly concerned with the means for securing the trim 8 to the frame 1. The frame 1, as specified above, is in the form 45 of a reverse J and is preferably made from steel having some spring action so that the lower portion of the frame forms a longitudinally extending spring pocket 9 having a mouth 10. The trim 8 is lapped around the outside of the pocket 50 9, then over the edge and positioned along the inside of the pocket as at 11. It will be noted that the edge portion 11 of the trim 8 is raw. This has a material advantage in that no accurate measurement of the size of the trim material 8 55 is necessary in order to properly fit the edge

portion 11 within the pocket 9. In other words, where the trim is provided with a beaded or corded edge, such as is well-known in the art, an absolutely accurate measurement of the size of the trim and the frame must be had to secure 5 an accurate fit between the trim and the frame. By making it possible to use the raw edge of the trim material this accurate measurement of the trim 8 relative to the seat frame is obviated. To retain the edge portion 11 of the trim within 10 the pocket 9 it is proposed to use a rod of any suitable cross section, such as a cylindrical rod 12. This rod 12 may be in a continuous length approximately equal to the length of the side member of the frame 1 in conjunction with which it 15 is used. However, preferably each rod member is approximately an inch long. By making each rod 12 such a short length the assembly of the rod in the pocket 9 is facilitated.

The diameter of each rod 11 is a little larger 20 than the mouth 10 of the pocket 9 of the frame 1 so that necessarily the pocket 9 is sprung outwardly during the insertion of the rod 11 through the mouth 10 into the pocket and the rod is resiliently or yieldably held in the pocket 9 due to 25 the spring action of the steel from which the frame is made. This spring engagement between the rod 11 and the pocket 9 securely retains the rod within the pocket.

It is very important in a spring cushion seat of 30 this type in which the seat springs 6 are constantly being loaded and unloaded and the rebound and tension of the springs are carried by the trim 8, to securely bind or tie the trim 8 to the frame 1. This is achieved by forming the 35 outer surface of each rod 11 so that it will bite into and firmly grip the trim material. This result may be achieved in several ways such as by longitudinally serrating the rod 12 as at 13 (Figs. 2 and 3) or by providing the rod with circumferential serrations 21 (Fig. 4), by knurling the outer surface of the rod, by threading the same or otherwise roughening the outer surface of the rod so that it will have a plurality of projections which bite into the edge portion 11 of the trim 45 material and securely tie it in the pocket 9 and to the frame 1.

I claim:

1. In a spring cushion seat having a bottom frame member provided with a spring pocket, 50 trim material for covering the seat springs and arranged to be drawn about the frame member and into the said pocket in overlapping relation with the spring pocket and a rod-like tie-down member the surface of which is provided with a 55

plurality of projections, the said tie-down members having a diameter somewhat larger than the mouth of the pocket and arranged to be forced through the said mouth of the pocket into the said pocket to clamp the edge of the trim material to the said frame.

2. In a spring cushion seat having a bottom frame member provided with a spring pocket, trim material for covering the seat springs and arranged to be drawn about the frame member and in overlapping relation with the resilient pocket and a rod-like tie-down member, the surface of which is provided with a plurality of grooves, the said tie-down member having a diameter somewhat larger than the mouth of the pocket and arranged to be forced through the said mouth into the said pocket to clamp the edge of the trim material in said pocket and to the said frame.

20 3. In a seat cushion comprising a steel frame member having a spring action and a cross section in the form of a reversed J, a plurality of springs, and a web of trim material for covering the said springs and arranged to be drawn about the frame member and have its edge inserted in the pocket of the reverse J frame member, a rod having a grooved surface and a diameter somewhat larger than the mouth of the reversed J member arranged to be forced through the mouth of the frame member against the edge portion of the trim positioned in the said pocket whereby the pocket of the J frame is placed under tension and cooperates with the grooved rod to securely tie the trim material to the said frame.

35 4. In a spring seat cushion comprising a frame member of spring steel having a cross section in the form of a reversed J to form a pocket extending along the inside of the frame, a plurality of slats extending from one portion of the frame member to the opposite portion of the frame member for tying the two portions together, coil springs supported by said slats, trim material for covering the said springs and frame member arranged to have its edge portion wrapped around

the outside of the frame member and positioned within the said pocket, a rod having a plurality of projections on its surface and a greater diameter than the width of the mouth of the pocket in the said reversed J frame member whereby the 5 said rod can be forced through the mouth of the spring pocket member between two consecutive slats and cooperate with the spring action of the pocket member to securely tie the edge portion of the trim material in the said pocket.

10 5. In a spring seat cushion comprising a frame member of steel having a spring action and a cross section in the form of a reversed J to form a pocket extending along the inside of the frame, a plurality of slats extending from one frame 15 portion to the opposite portion for tying the two portions together, coil springs supported by said slats, trim material having a raw edge for covering the said springs and frame member arranged to have its raw edge portion wrapped around the 20 outside of the frame member and positioned within the said pocket, a rod having a greater diameter than the width of the mouth of the pocket in the said reversed J frame member, the said rod having a plurality of serrations on its surface 25 whereby the said rod can be forced through the mouth of the spring pocket member and cooperate with the spring action of the pocket member to securely tie the raw edge portion of the trim material in the said pocket.

30 6. A trim assembly comprising a metal frame member having a channel portion with spring walls spaced to form a mouth, trim material having an edge portion for insertion in the spring mouth of the frame member and a rod tie-down 35 member the surface of which is provided with a plurality of projections, the said tie-down member having a diameter somewhat larger than the mouth of the pocket and arranged to be forced through the mouth of the pocket into the pocket to cooperate with the spring action of the spring channel walls and thereby clamp the edge of the trim material to the said frame.

40 MAURICE STUBNITZ.
